UNITED STATES PATENT OFFICE.

MARSHALL C. LEFFERTS, OF NEW YORK, N. Y., ASSIGNOR TO THE CELLULOID COMPANY, OF SAME PLACE, A CORPORATION OF NEW JERSEY.

DESIGN FOR A RAZOR-HANDLE.

SPECIFICATION forming part of Design No. 27,092, dated May 25, 1897.

Application filed April 10, 1897. Serial No. 631,633. Term of patent 7 years.

To all whom it may concern:

Be it known that I, MARSHALL C. LEFFERTS, a citizen of the United States, residing in the city, county, and State of New York, 5 have invented and produced a new and original Design for Razor-Handles and the Like, of which the following is a specification.

My invention relates to designs for razor-handles and the like; and it consists in the 10 article provided with the ornamentation substantially as hereinafter described.

In the drawings forming part of this specification, Figure 1 is a side elevation, and Fig. 15 2 an end elevation, ornamented by my design.

The handle, of conventional form, is ornamented on its exterior parts 1 2 as follows: On the exterior and at the base of each of the 20 parts 1 2 are produced in relief a series of concentric foliated figures 3, their ends 4 curving inwardly, the central figures being

slightly raised above the edge figures, and between the ends of the foliated figures are rows of graduated beads 5. The upper end of each of the parts 1 2 are provided with a foliated 25 figure having a central portion 6 and two radiating portions 7 8, between which are the rows of graduated beads 9 and single beads 10.

As shown in Fig. 2, the exterior transverse surface of the parts 1 2 between the two ends 30 is convex and provided with cross-lines 11, forming a continuous series of rectangular projections 12.

Having described my invention, I claim—

The design for razor-handles, and the like, 35 substantially as herein shown and described.

Signed at the city, county, and State of New York this 8th day of April, 1897.

MARSHALL C. LEFFERTS.
